UNITED STATES PATENT OFFICE.

MAX KLEIN, OF BROOKLYN, NEW YORK, ASSIGNOR TO SHAPIRO AND ARONSON, INC.,
OF NEW YORK, N. Y., A CORPORATION OF NEW YORK.

DESIGN FOR A TABLE LAMP.

Application filed September 23, 1925. Serial No. 14,876. Term of patent 7 years.

To all whom it may concern:

Be it known that I, MAX KLEIN, a citizen of the United States, residing at Brooklyn,

in the county of Kings and State of New York, have invented a new, original, and ornamental Design for Table Lamps, of which the following is a specification, reference being had to the accompanying drawing forming part thereof.

Fig. 1 is a front view showing my new design.

Fig. 2 is a plan view of the lamp in which

certain details of the base ornamentation

are shown.

I claim:

The ornamental design for a table lamp,

as shown.

MAX KLEIN.
